UNITED STATES PATENT OFFICE.

CARL SIGFRID NYBERG, OF HASSELBACKEN, MELLÖSA, SWEDEN.

SPLIT BELT-PULLEY.

1,145,078.

Specification of Letters Patent.

Patented July 6, 1915.

Application filed February 9, 1911. Serial No. 607,623.

To all whom it may concern:

Be it known that I, CARL SIGFRID NYBERG, a subject of the King of Sweden, and resident of Hasselbacken, Mellösa, in the Kingdom of Sweden, have invented certain new and useful Improvements in Split Belt-Pulleys, of which the following is a specification, reference being made to the accompanying drawing.

10 The present invention refers to a split belt pulley which is chiefly characterized by there being arranged around the parts a band serving as a ring, the ends of which band are united at the inner side of the ring by means of bolts or some other suitable device, by the tightening of which not only the parts of the pulley are kept together, and the pulley is fastened on its shaft but by means of which, also, said band or ring may be curved 20 or made convex in cross section.

In the accompanying drawing there is shown a form of construction of a pulley in accordance with this invention.

Figure 1 shows the pulley seen from the 25 side, and Fig. 2 the same seen in plan. Figs. 3 and 4 show in section two forms of the rim of the pulley.

The pulley, which can consist of two or several parts is, in the drawing, shown as 30 consisting of two parts. Over the rim of the two parts there is arranged a band 1, the ends 2 and 3 of which are bent inward toward the center of the pulley, and enter into one of the two openings between the 35 parts of the pulley. The knees 4 of the ends 2 and 3 are so arranged on the band, that the said knees are at a little distance from each other, when the two halves are in the position relative to each other that they ought 40 to have after being placed on their shaft. Through the ends 2 and 3 pass one or several (usually two) bolts 5, the number being dependent, partly on the breadth of the ring and partly on the shape of the rim of the 45 pulley parts. On tightening the bolts, the ends 2 and 3 ought to rest against each other at 6, for which reason the ends at this place are preferably bent over, or a suitable plate or other member is interposed between 50 these ends. Instead of the ends of the band being bent over, there can be fastened at the ends of the band suitable angle iron pieces, through which the bolts 5 are drawn. When two or more bolts are employed the

size of ring can be varied by tightening the 55 outermost bolts more or less, and by this action, also, the cross sectional curvature of the ring may be suitably varied.

In order, on the one hand, to easily center the band on the rim, and, on the other hand, to prevent the band from being pushed to the side or sliding off the rim, there are arranged on the inner side of the band stamped or pressed elevations 7, which in the form of the rim shown in Figs. 2 and 3, are situated at the sides of said rim, and, in the form shown in Fig. 4, enter into a groove or the like, arranged in the rim. These elevations can, if so desired, be in the form of ridges along the length of the band, or can 65 be replaced by projecting pieces or rods fastened to the inner side of the band, which pieces or rods can also be employed to stiffen the band if this be necessary.

It can easily be seen that the section of the 75 rim of the pulley parts can have other forms than the V-form shown in Fig. 3, or the T-form shown in Fig. 4.

It is clear that the arrangement described above can be employed with pulleys of metal 80 as well as of wood, and that it is independent of the device at the nave, and this, whether there be used at the nave special bolts for the fastening to the shaft or not.

Having now described my invention, 85 what I claim as new and desire to secure by Letters Patent is:

A pulley comprising a plurality of pulley sections, each section consisting of a hub portion, spokes and a rim segment, a flexible band placed loosely around said rim segments and constituting a continuous rim by means of which said sections are held together and secured to a pulley shaft, and means at one point of said band for adjustably connecting the ends of said band together, said last named means including extensions of said band turned toward the pulley center, the ends of said extensions bearing against each other and having a 95 bolt connection therethrough.

In witness whereof I have hereunto set my hand in presence of two witnesses.

CARL SIGFRID NYBERG.
